UNITED STATES PATENT OFFICE.

ALBERT H. JOHNSON, OF WASHINGTON, DISTRICT OF COLUMBIA, ASSIGNOR TO NATIONAL ELECTRICAL SUPPLY COMPANY, OF WASHINGTON, DISTRICT OF COLUMBIA, A CORPORATION OF VIRGINIA.

MACHINE FOR CRIMPING WIRE.

1,345,445.

Specification of Letters Patent.

Patented July 6, 1920.

Application filed January 21, 1920. Serial No. 352,994.

To all whom it may concern:

Be it known that I, ALBERT H. JOHNSON, a citizen of the United States, residing at Washington, in the District of Columbia, 5 have invented certain new and useful Improvements in Machines for Crimping Wire, of which the following is a specification.

This invention relates to machines for crimping wire, and it comprises a source of 10 supply, means for holding the wire to be crimped, means for progressively feeding the wire through the machine as it is crimped, means for bending the wire alternately to each side of said holding means 15 to crimp the wire, and operating means to supply oscillating motion to said wire bending means, and intermittent rotary motion to said wire feeding means, all as more fully hereinafter set forth, and as claimed.

20 In crimping wire, it is necessary to provide means for feeding the wire to the machine, intermittently; the wire is fed into position to form a crimp or loop, the feeding motion is arrested during the crimping 25 operation and then operated again to bring a new section of wire into position for crimping. While the portion of wire to be crimped is held stationary between two operations of the feeding mechanism, some 30 means are employed to bend the remaining portion with respect thereto, and form one of the loops at the end of each crimped section.

In the present invention, I utilize the reciprocating motion of a milling machine, 35 planer or like apparatus as a source of power. The wire is fed from a source of supply between a pair of grooved rollers mounted on a bracket. The bracket is mounted on a shaft, and is adapted to swing 40 in the arc of a circle due to oscillation of said shaft. Thence the wire passes between a pair of rollers, spaced from each other sufficiently to permit the wire to pass therebetween, but being arranged so as to apply a 45 pressure to the wire sufficient to hold it while the arms or bracket is swinging. The rollers are arranged in alinement with the center of the arc through which the arm or bracket oscillates, and it will thus be apparent that the swinging of the arm from 50 one side of the rollers to the other, bends or loops the wire just above the rollers and causes a crimp.

The wire is fed through the machine by

intermittent rotation of the rollers, the feed 55 means being so arranged that it is at rest during the oscillation of the crimping arm and in operation during intervals between the oscillation of the crimping arm.

The feeding means and crimping means 60 are both driven from the reciprocating tool holder of a milling machine, planer, or like apparatus through the provision of novel means forming a part of this invention. Oscillation of the shaft carrying the crimping arm is obtained through the provision of a rack bar, carried by the reciprocating head, or stock, and engaging a gear wheel on said shaft. The rack bar engages the teeth of the gear during only a portion of 65 its reciprocation, producing the effect of a mutilated gear, and causing an interval between each oscillation of the shaft, the shaft oscillating while the gear and rack bar are in engagement, and remaining idle 70 during the remainder of the reciprocation of the rack bar.

The rollers are driven from the same source of power by means of a pawl and ratchet arrangement mounted on a shaft, 80 and geared to the shaft carrying the rollers. The ratchet wheel is provided with ratchet teeth adapted to be alternately engaged by one of two oppositely disposed spring 85 pressed pawls or dogs, the pawls being connected by links to a pivoted arm carrying a projection or lug. This arm is arranged in the path of a reciprocating element which is adapted to move the arm on its pivot and thus bring one of the dogs into engagement 90 with the ratchet teeth through the link connection. These parts are so arranged that the intermittent rotation of the rollers takes place in the intervals between oscillations of the crimping mechanism.

95 In the accompanying drawings, I have shown an advantageous embodiment of this invention.

In this showing:

Figure 1 is a partial side elevation of the 100 machine,

Fig. 2 is a plan view of a part of the machine showing the crimping arm and the crimping rolls,

Fig. 3 is a transverse sectional view on 105 line 3—3 of Fig. 1,

Fig. 4 is a detail perspective view of the reciprocating element that engages the

pivoted arm to operate the pawl and ratchet mechanism,

Fig. 5 is a detail perspective view of the crimping arm,

5 Fig. 6 is a detail perspective view of take-up means arranged in the wire feed,

Fig. 7 is a detail sectional view showing the construction of the pawl and ratchet mechanism,

10 Fig. 8 is a sectional view through the ratchet wheel at right angles to Fig. 7,

Fig. 9 is a sectional view showing one of the crimping rolls and illustrating the position of the crimping arm at the extreme 15 right,

Fig. 10 is a similar view, illustrating the position of the crimping arm at the extreme left, and,

20 Fig. 11 is a sectional view through the crimping rolls at right angles to Fig. 9.

Referring in detail to the drawings, the numeral 1 designates the bed or carriage of the machine upon which is mounted a reciprocating stock 2, driven in any suitable manner. The specific driving means for the stock, form no part of the present invention, and a detailed description thereof, is omitted. The stock is provided with the usual tool post 3, having a vertical opening 4 therein, 30 and provided with a set screw 5, for fastening a tool in the tool post 3. A rod 6 is mounted in the tool post, the rod being connected at one end to a horizontal rack bar 7. A portion of this rack bar is provided with 35 rack teeth 8, which are adapted to mesh with gear 9, mounted on shaft 10. This shaft carries the crimping arm 11, shown in detail in Fig. 5 of the drawings. As shown, the crimping arm consists of a substantially L-shaped body portion, having an opening 12, for the reception of the shaft. The opening is provided with a groove 13, and shaft 10 is provided with a similar groove (not shown), for the reception of a key, whereby 40 the crimping arm is rigidly secured to the shaft and moves therewith. A pair of rollers 14 and 15 are arranged upon the opposite end of the crimping arm and these rollers are provided with peripheral grooves 17, 50 for the reception of the wire (see Figs. 9 and 10). The mechanism just described produces an oscillating motion of the shaft 10 and the crimping arm 11. The mechanism is so arranged that the crimping arm 55 oscillates substantially in a semi-circle. The number of teeth on the horizontal bar are so proportioned that the gear 9 is not oscillated throughout the entire reciprocating stroke of the bar, thus producing an 60 interval between oscillations.

The mechanism for imparting intermittent rotary motion to the crimping rollers is as follows:

65 Rollers 18 and 19 are mounted on shafts 21 and 22 journaled in the brackets 23 and

24, carried by the bed of the machine. The rollers are spaced from each other sufficiently to permit passage of the wire between them, but sufficiently close to each other to permit them to hold the wire securely during the crimping operation. As 70 shown, one of the rollers is mounted in adjustable bearings and may be regulated through the provision of screw 25, and adjustable plate 26 (see Fig. 11). The shafts 75

21 and 22 are provided with gears 27 and 28, upon one end, and are driven from the main shaft 29, through a worm 30, and gears 31 and 32. The gear 31 is mounted on a stub shaft 33 and meshes with the worm. 80 This gear is also in mesh with gear 27 on shaft 21, driving the roll 18 in a clockwise direction. The gear 32 is mounted on a stub shaft 34, and meshes with the gear 31. This gear also engages gear 28 on shaft 22 to 85 revolve the roll 19 in a counter clockwise direction.

Mounted on the main shaft 29, is a ratchet wheel 35 provided with ratchet teeth 36. A pair of arms 37 and 38 are arranged to 90 revolve freely on the main shaft, the arms extending over each side of the ratchet wheel. Dogs or pawls 39 and 40 are pivoted to these arms, at 41 and 42, and are adapted to engage the ratchet teeth on the 95 ratchet wheel. These pawls are held in engagement with the ratchet teeth by springs 43 and 44. As shown, the arms are connected to a pivoted arm 45, by means of links 46 and 47. The pivoted arm is mounted in 100 a bracket 48, arranged on the bed of the machine, and as shown, is pivoted thereto at 49. A projecting head or lug 50 is carried by this pivoted arm. As the pivoted arm is 105 swung upon its pivot, it causes rotation of the main shaft by bringing one of the pawls into engagement with the ratchet teeth, as illustrated in Fig. 7. As illustrated in the full line position in this figure, the pivoted arm is in one position and is adapted to be 110 moved to the position shown in dotted lines. When moved to the dotted line position, the links 46 and 47 cause the arms 37 and 38 to swing to the right and pawl 40 engages the ratchet teeth to revolve the shaft. When 115 the pivoted arm 45 is returned to full line position, the links move the arms to the full line position and pawl 39 engages the ratchet teeth to revolve the shaft.

The means for swinging the pivoted arm 120 are as follows:

At the upper end of the rod 6, secured in the tool post, there is provided a reciprocating bar 51, provided with lateral offsets 52 and 53. Mounted in each of these offsets 125 are set screws 54 and 55. As the bar 51 reciprocates, the set screws contact with the lug 50 on the pivoted arm and cause the arm to swing on its pivot. The set screws are provided for the purpose of adjusting the 130

intervals between rotation of the rollers. The provision of the set screws is not essential and they may be eliminated and the pivoted arm actuated by contact between the lateral extensions 52 and 53, and the projection 50.

The wire is fed to the rollers from a reel 56, mounted in a frame 57, carried by a portion of the frame work of the machine. As shown, the frame is mounted on a vertical post 58. The reel is held in bearings 59 and 60 which, as shown, are threaded to permit removal and insertion of the reels. Nuts 61 and 62 are provided to hold the bearings in position. Brake 63 is adapted to engage the end 64 of the spool on which the wire is mounted. This brake supplies the tension to the wire. The brake may be provided with a face of friction material 65. It is supported from the frame or bracket 57, by a spring arm 66, fastened to the bracket by nut and bolt 67. The pressure of the spring may be adjusted by threaded bolt 68, which bears against the spring arm. This adjustment permits variation of the tension on the wire. From the reel, the wire 69 is fed over a grooved roller 70, carried by take-up arm 71, which is pivoted in a bracket 72. The end of the arm is connected to a coiled spring 73, which is secured to the frame work of the machine at 74. When the crimping arm is in position shown in Figs. 9 and 10 of the drawings, the wire is taut, but when it swings from one position to the other the wire becomes slack. Spring 73 pulling upon the free end of the take-up arm causes the opposite end to raise and take up the slack in the wire.

A stop 71' is arranged near the take-up arm and is adapted to come in contact with the take-up arm before the crimping arm 11 reaches the position illustrated in Fig. 9 or Fig. 10 of the drawings. This prevents further downward movement of the take-up arm and the pull on the wire causes wire to be fed from the reel. The amount of wire so fed should be sufficient to form one crimp.

From the roller 70, the wire is carried between the grooved rollers on the crimped arm and thence to the crimping rollers. An opening 75, is arranged in the frame work of the machine beneath the crimping rollers, to permit removal of the crimped wire from the machine.

The operation of this device is as follows:

When the machine is to be started, the wire is fed by hand over the grooved take-up roller 70, between the grooved rollers of the crimping arm and thence to the crimping rollers. The reciprocation of the stock 2 reciprocates rack bar 7, carried thereby, and oscillates gear 9. The oscillation of gear 9, causes the crimping arm 11 to swing in a substantial semicircle, or arc of a cir-

cle, from the position shown in Fig. 9, to the position shown in Fig. 10, and vice versa. The crimping rollers are arranged substantially in alinement with shaft 10, and thus with the center of oscillation of 70 the crimping arm. By reference to Figs. 9 and 10, it will be seen that this oscillation of the crimping arm bends the portion of wire just beyond the crimping rollers to form a loop. As stated, the number of teeth 75 upon the rack bar are so proportioned to the teeth upon the gear wheel 9, that the crimping arm is oscillated in a substantial semicircle. The rack bar does not engage the gear wheel throughout its entire stroke, 80 thus producing an interval between two oscillations of shaft 10 and the crimping arm. During the interval between two oscillations, the crimping rollers are rotated to feed the crimped wire a predetermined distance through the machine so that the last crimp formed is always securely held between the rollers and the free portion of the wire just beyond the rollers is bent or crimped during the next oscillation. The 90 crimping rollers are rotated from shaft 29, through the provision of gearing, previously described, and the shaft is intermittently rotated through the provision of ratchet wheel 35 and pawls 39 and 40. At each re- 95 ciprocation of the stock, one of the lateral extensions 52 and 53 on the reciprocating bar 51, engages the projection or lug 50, and rotates the shaft through the link connections.

The provision of the take-up roller 70 is 100 advantageous, as I find that otherwise the wire would become slack during the oscillation of the crimping arm. This slack is automatically taken up by the swinging of arm 71, due to the tension of springs 73.

In the drawings, I have shown the rollers 105 18 and 19 provided with roughened surfaces. The provision of such roughened rollers is for the purpose of flattening and roughening the straight sections of wire 110 between two loops to produce a resistance wire in accordance with my co-pending application, Serial No. 345,972, filed December 19, 1919. When it is desired to produce the ordinary crimped wire, the rollers are replaced by rollers having a smooth surface, 115 and the pressure of the rollers is adjusted to that sufficient to hold the wire without flattening it.

It is to be understood that the form of 120 my invention herewith shown and described is to be taken as a preferred example of the same, and that various changes in the shape, size, and arrangement of parts may be resorted to without departing from the spirit 125 of my invention or the scope of the subjoined claims.

Having thus described my invention, I claim:

1. A wire crimping machine, comprising 130

- 5 a pair of rollers adapted to receive and hold the wire to be crimped, an oscillating crimping arm arranged near said rollers, said arm being provided with wire receiving means whereby the wire is bent to either side of the rollers and crimped, means for oscillating said arm, and means for intermittently rotating said rollers.
- 10 2. A wire crimping machine, comprising a pair of rollers adapted to receive and hold the wire to be crimped, an oscillating crimping arm arranged near said rollers, said arm being provided with wire receiving means whereby the wire is bent to either side of the rollers and crimped, a shaft on which said crimping arm is mounted, driving means for said shaft, said means comprising a reciprocating rack bar, and a gear on said shaft meshing with said rack bar to oscillate said crimping arm and bend said wire to either side of the rollers and crimp the wire.
- 15 3. A wire crimping machine, comprising a pair of roughened rollers adapted to receive and hold the wire to be crimped, an oscillating crimping arm arranged near said rollers, means for oscillating said arm at intervals whereby the wire is bent to either side of the rollers and crimped, said rollers being held together with sufficient pressure to roughen the sides of the wire, and means for intermittently rotating said rollers during the intervals when said arm is at rest.
- 20 4. A wire crimping machine, comprising a pair of rollers adapted to receive the wire to be crimped, an oscillating crimping arm arranged near said rollers, a shaft on which said crimping arm is mounted, a gear carried by said shaft, a reciprocating rack bar meshing with said shaft, said gear and said bar being in engagement during a portion of its reciprocation to oscillate said crimping arm at intervals.
- 25 5. A wire crimping machine, comprising a pair of roughened rollers adapted to receive and hold the wire to be crimped, an oscillating crimping arm arranged near said rollers, means for oscillating said arm at intervals whereby the wire is bent to either side of the rollers and crimped, the roughened portions of said rollers being adapted to roughen the surface of the wire passing between them, a main drive shaft, gearing connecting said rollers to the main drive shaft to drive said rollers in opposite directions, and means for intermittently rotating said shaft.
- 30 6. A wire crimping machine, comprising a pair of rollers adapted to receive the wire to be crimped, an oscillating crimping arm arranged near said rollers, means for oscillating said arm at intervals, a main drive shaft, gearing connecting said rollers to the main drive shaft to drive said rollers in opposite directions, a ratchet wheel mounted on said shaft, pawls adapted to engage said ratchet wheel to intermittently rotate said shaft, and means for causing said pawls to engage said ratchet wheel.
- 35 7. A wire crimping machine comprising a pair of rollers adapted to receive the wire to be crimped, an oscillating crimping arm arranged near said rollers, means for oscillating said arm at intervals, a main drive shaft, gearing connecting said rollers to the main drive shaft to drive said rollers in opposite directions, a ratchet wheel mounted on said shaft, pawls adapted to engage said ratchet wheel to intermittently rotate said shaft, pivoted arms on which said pawls are mounted, links connected to said arms, a pivoted arm to which said links are connected, and means for moving said arm to cause the pawls to alternately rotate the ratchet wheel.
- 40 8. A wire crimping machine, comprising a pair of rollers adapted to receive the wire to be crimped, an oscillating crimping arm arranged near said rollers, means for oscillating said arm at intervals, and means for intermittently rotating said rollers during the intervals between oscillation of said shaft, means for feeding wire to be crimped to said crimping arm and said rollers, and automatic tensioning means connected to said feeding means.
- 45 9. A wire crimping machine, comprising a pair of roughened rollers adapted to receive the wire to be crimped, an oscillating crimping arm arranged near said rollers, means for oscillating said arm at intervals, means for intermittently rotating said rollers between the oscillation of said crimping arm to progressively feed the wire to the rollers, and tensioning means through which said wire passes, said means being adapted to automatically tension the wire fed to the rollers.
- 50 10. A wire crimping machine, comprising a pair of roughened rollers adapted to receive the wire to be crimped, an oscillating crimping arm arranged near said rollers, means for oscillating said arm at intervals, means for intermittently rotating said rollers between the oscillation of said crimping arm to progressively feed the wire to the rollers, and tensioning means through which said wire passes, said means being adapted to automatically tension the wire fed to the rollers, the roughened surface of the rollers being adapted to roughen the portion of the wire between the crimped portions.

In testimony whereof I affix my signature in presence of two witnesses.

ALBERT H. JOHNSON.
